UNITED STATES PATENT OFFICE.

HARRY S. GRAVES, OF DETROIT, MICHIGAN, ASSIGNOR TO SPIRAL PISTON RING COMPANY, OF DETROIT, MICHIGAN, A CORPORATION OF MICHIGAN.

APPARATUS FOR ELECTRICALLY FORMING SPIRAL PISTON RINGS.

Application filed August 15, 1925. Serial No. 50,532.

This invention relates to piston ring forming machines and my invention aims to provide a machine in which split circular rings may be expeditiously and economically converted into spiral rings which may be advantageously used in connection with various types of pistons, particularly for internal combustion engines.

My invention further aims to provide a machine for gripping split piston rings, subjecting the rings to heat, and then offsetting one end of the ring for a spiral formation, the ring being released to drop into a tempering bath which sets the spiral formation of the ring.

My invention still further aims to provide a process of offsetting split rings to impart a spiral formation thereto, the process including progressively performed operations, to wit:—first, holding the split ring so that one end thereof may be shifted at an angle to the plane of the ring; second, electrically heating said ring by passing an electric current through the ring and its holding means; third, shifting an end of the ring, during the application of heat, to offset such end relative to the other end of the ring, and then releasing the ring so that it may be tempered.

My invention includes an organization of instrumentalities by which rings may be safely heated by electricity, and the construction entering into the machine will be hereinafter specifically described and then claimed.

Reference will now be had to the drawings, wherein—

Figure 1 is a front elevation of the machine partly in section;

Fig. 2 is a plan of the machine partly in section;

Fig. 3 is a vertical cross sectional view of the machine;

Fig. 4 is a view of one end of the machine;

Fig. 5 is a view of the opposite end of the machine;

Figs. 6 to 8 inclusive are diagrammatic views of ring gripping jaws showing the forming of a spiral ring from an ordinary split ring;

Fig. 9 is a perspective view of a split or embryo ring, and

Fig. 10 is a similar view of the same ring after having a spiral formation imparted thereto.

In the drawings, the reference numeral 1 denotes a work bench or table and suitably secured thereto by bolt equipped nuts 2 or other fastening means is an overhanging support 3 having its front edge recessed, as 4, to provide clearance for a set of ring gripping jaws that will be hereinafter described.

Mounted on the ends of the support 3 are brackets 5 and 6 and attached to said brackets by screws 7 or other fastening means is a double T-head 8 having its front and rear sides provided with slide-ways 9 and one end cut away, as at 10.

In the rear guideway of the head 8 are jaw blocks 11 and 12 and in the front guideway are jaw blocks 13 and 14. The jaw blocks 11 and 12 have a set of depending jaws 15 adapted to cooperate with another set of jaws 16 carried by the blocks 13 and 14 for gripping the split end portions 17 of a ring 18, best shown in Fig. 9. The jaw blocks 11 to 14 inclusive have a dove-tail connection with the head 8 and all of the jaw blocks are slideable in said head, with the exception of the jaw block 14 which is fixed to the head by a screw bolt 19 or other fastening means. The jaws 15 and 16 are insulated from the blocks 11 and 14 inclusive by insulation washers 20 and insulation sleeves 21, said washers and sleeves accommodating nut equipped bolts 22 by which the jaws are connected to the blocks and said nut equipped bolts serve as binding posts, as will hereinafter appear.

Interposed between the confronting ends of the blocks 11 and 12 and the confronting ends of the blocks 13 and 14 are coiled light duty springs 23 adapted to have the expansive force thereof hold the jaw blocks 11 and 13 open relative to the jaw blocks 12 and 14 so that the split end portions 17 of the ring 18 may be easily placed between the jaws of each set to be gripped and temporarily held thereby.

Slidable in the guideways of the head 8 are cross heads 24 and interposed between said cross heads and the blocks 11 and 13 are heavy duty coiled expansion springs 25. The cross heads 24 are provided with adjustable abutments 26, preferably in the form of screw bolts, adapted to be engaged by cam engaging members 27 slideable in the guideways of the head 8. These cam engaging members are normally engaged by a

cam 29 mounted on the end of a shaft 30, journaled in the bracket 5. The opposite end of the shaft has a cam 31 and a sprocket wheel 32.

5 Journaled in the bracket 6 is a shaft 33 provided with a sprocket wheel 34 and a cam 35, said cam being adapted to engage the jaw block 12 and shift this block along with the block 11 so that the set of jaws 15 10 may be shifted relative to the set of jaws 16.

Trained about the sprocket wheels 32 and 34 is an endless sprocket chain 36 adapted to be driven by a sprocket wheel 37 on a shaft 38, journaled in a gear housing 39 15 suitably secured to the support 3. In the gear housing 39 and on the shaft 38 is a worm wheel 40 meshing with a worm 41 adapted to be driven from an electric motor 42 mounted on the support 3. The motor 20 42 may be driven from a suitable source of energy and its operation controlled by a conventional form of switch. The sprocket wheels and chain are a fair example of a power transmission mechanism by which the 25 shafts 30 and 33 may be driven in synchronism, and while the cams are adapted for shifting the slidable blocks, cross heads and cam engaging members in certain directions, the springs 23 and 25 are adapted for shifting 30 the slidable blocks, cross heads and cam engaging members in other directions.

On the support 3, preferably at the rear side thereof, is an insulator 43 provided with connectors 44 for leading in wires 45 from 35 a suitable source of electrical energy. One of the connectors 44 is connected by wires 46 to the set of jaws 15 and the other connector is connected by a wire 47 to a contact member 48 mounted at a switch housing 49 suitably supported from a head 8. In the switch housing 49 is pivotally mounted a spring pressed lever 50 which extends 40 through an opening 51 in the bottom of the switch housing and has an angular end 52 in the path of the cam 31 so as to be actuated 45 thereby. The upper or opposite end of the pivoted lever 50 has a contact member 53 adapted to engage the contact member 48 and complete an electric circuit. The contact member 53 is connected by a wire 54 50 to a binding post 55 of the switch housing and said binding post is connected by wires 56 and 57 to the set of jaws 16. The contact members 48 and 53 and the binding post 55 are suitably insulated from their supports. 55

When the motor 42 is placed in operation the shafts 30 and 33 are driven in synchronism and the jaw blocks 11, 12 and 13 are shifted so that the jaws are caused to grip 60 the split end portions 17 of the ring 18 and then hold one end of the ring while the opposite end of the ring is shifted to offset it relative to the plane of the ring, thereby imparting a spiral formation to the ring, as 65 shown in Fig. 10. The jaw block 14 being

stationary and the jaw block 12 abutting the cam 35 permits the expansive forces of the springs 23 and 25 to at all times retain the cam engaging members 27 in engagement with the cam 29. When the cam 29 becomes 70

active the members 27 and the blocks 24 are shifted towards the jaw blocks 11 and 13 and by virtue of the heavy duty springs 25 the jaw blocks 11 and 13 are moved towards the jaw blocks 12 and 14 which are now stationary. The light duty springs 23 are compressed and the split end portions 17 of the ring 18 are clamped between the jaws 15 and 16 with the plane of the ring at a right angle to the direction of travel of said jaws. 80

With the ring gripped by the jaws the cam 31 actuates the pivoted lever 50 and closes an electric circuit at the contact members 48 and 53 whereby there is current flowing through the jaws 15 about the ring 85 18 to the jaws 16, thus causing the ring 18 to be heated to such an extent that it may be reshaped or easily distorted. The electrical connections are clearly shown in Figs. 6 to 8 inclusive and by observing these views it 90 will be noted that a circuit may be provided by simply making connections with one jaw of each set, but by having electrical connections about all of the jaws a better electrical contact is established with the 95 sides of the ring for heating purposes.

When the ring is in a heated condition the cam 35 actuates the jaw block 12 and through the medium of the spring 23 between the blocks 11 and 12, said blocks are 100 shifted in synchronism carrying the set of jaws 15 out of transverse alinement with the set of jaws 16, thereby offsetting one end portion of the split ring relative to the other end portion, thus imparting the spiral formation to the ring. Next, the cams 29, 31 and 35 permit the current to be shut off and the jaws opened to release the offset ring so that it may drop into a tempering bath 58 in a receptacle 59 placed below the 105 jaws 15 and 16. The expansive forces of the springs 23 and 25 cause the jaws to assume normal position so that another ring may be immediately placed in position by an attendant of the machine to have a spiral formation imparted thereto. 110

If no ring is in position to be gripped by the jaws there is no contact of the jaws and consequently no electrical circuit completed, because it requires a ring in position and gripped by the jaws to complete an electric heating circuit. The operation of the machine is timed so that each ring will be thoroughly heated before being offset and the only manual operation, after starting the machine, is that of placing rings in position to be gripped by the jaws. 115

From the foregoing operation of the machine it will be noted that a process is involved that may be carried into effect by a 130

machine that may be structurally different from the machine herein shown, but the process necessarily includes some means of holding the ring in order to subject it to heat and 5 then offset one end of the ring relative to the other end so as to impart a spiral formation to the ring. I prefer to accomplish the heating through the same means which holds the ring and offsets it, and I find that electricity 10 can be advantageously used for heating purposes. In view of these facts I do not care to confine my invention to any particular type of machine other than set forth in the appended claims.

15 What I claim is:—

1. A machine of the type described, comprising clamping means for the ends of the split ring, means for electrically heating said ring by the application of current to 20 said clamping means, and means adapted for shifting a portion of said clamping means to impart a spiral formation to said ring.

2. A machine of the type described including sets of jaws adapted to grip the 25 ends of a split ring, means adapted to shift some of said jaws for ring gripping purposes, means set in action by the jaw shifting means for applying heat to said ring to render it malleable, and means adapted

30 to shift one set of jaws relative to the other set of jaws, during the application of heat, to impart a spiral formation to said ring.

35 3. A machine as called for in claim 2, wherein the jaw shifting means includes motor driven cams.

4. A machine as called for in claim 2, wherein the second mentioned means includes an electric circuit with said jaws in 40 said electric circuit.

5. A machine as called for in claim 2, wherein the second mentioned means includes an electric circuit and a cam actuated switch controlling said circuit.

6. A machine of the type described comprising a head, a set of jaws at each side of 45 said head and extending under said head for ring gripping purposes, jaw actuating means at the ends of said head to cause said jaws to grip a ring, electrical connection 50 for said jaws, and means adapted to move one set of jaws while the other set of jaws are held stationary.

7. A machine of the type described comprising a head, a set of jaws at each side of 55 said head and extending under said head for ring gripping purposes, jaw actuating means at the ends of said head to cause said jaws to grip a ring, electrical connections 60 for said jaws, a switch controlling the current to said jaws independent of the other set of jaws for offsetting an end of the ring, and switch operating means operable in the interim of gripping the ring and offsetting the ring.

8. A machine as called for in claim 7, wherein jaw actuating means and said switch operating means are coaxial and driven from a common source of power.

It testimony whereof I affix my signature.

HARRY S. GRAVES.
